UNITED STATES PATENT OFFICE

JOHN F. HUCKEL, OF KANSAS CITY, MISSOURI

DESIGN FOR A DISPLAY TABLE

Application filed November 18, 1929. Serial No. 33,485. Term of patent 3½ years.

To all whom it may concern:

Be it known that I, JOHN F. HUCKEL, a citizen of the United States, residing at Kansas City, in the county of Jackson and State of Missouri, have invented a new, original, and ornamental Design for Display Tables, of which the following is a specification, reference being had to the accompanying drawing, forming part thereof.

The figure is a perspective view of a display table, showing my new design.

I claim:

The ornamental design for a display table, as shown.

JOHN F. HUCKEL.
